UNITED STATES PATENT OFFICE.

CHARLES H. BECKER, OF WEST ALLIS, WISCONSIN, ASSIGNOR TO THE TURNER TANNING MACHINERY COMPANY, OF PORTLAND, MAINE, A CORPORATION OF MAINE.

MACHINE FOR TREATING HIDES, SKINS, AND LEATHER.

Application filed September 19, 1925. Serial No. 57,362.

This invention relates to machines for treating hides, skins and leather, and is illustrated as embodied in a machine designed for performing unhairing operations although

5 in various aspects the invention is not limited to embodiment in machines of the illustrated type or to use in performing the particular operations just referred to.

One well known type of machine for performing operations such as those above mentioned has been provided with a yielding member to support the work against the thrust of a bladed cylinder. As heretofore constructed such yielding, work-supporting 15 members have consisted of pneumatic rolls rotatably adjustable to present successive work-engaging portions in operative relation to the tool. These members have been relatively expensive to manufacture. Moreover, 20 each work-supporting portion of the surface wore away rapidly causing frequent adjustment to present an unworn surface in work-supporting relation to the tool, with the result that soon the entire roll became polygonal in cross-section unsuiting it for further use. This necessitated frequent replacement of the work-supporting members. In 25 other prior constructions the yielding work support has been furnished by one member, not adjustable to present successive surfaces in work supporting position, or by a plurality of members yielding individually to the thrust of the tool but not adjustable to present new surfaces in opposition to the tool.

30 Where a single-piece pneumatic work support is employed which is not adjustable it is of considerably shorter life than the adjustable type already referred to. In the construction employing a plurality of yielding work support members, worn members may be replaced locally along the length of the operating tool but that involves the necessity of constant inspection and frequent adjustment of the tensioning means for the members and frequent replacement as the members 35 become too worn to function properly.

In view of the foregoing, it is an object of the invention to provide an improved machine for treating hides, skins or leather 40 which will not be open to the objections above

stated and will be otherwise simple in construction, relatively inexpensive in upkeep, and readily adjustable by the ordinary workman.

To this end, and in accordance with important features of the invention, there is provided a flexible member to support the work against the thrust of the working tool in combination with pneumatic means for yieldingly backing the flexible member along 55 the line of application of the tool to the work. In a preferred construction, as illustrated the flexible member comprises a relatively inexpensive bolster which presents for co-operation with the treating tool and with the 60 pneumatic means a broader surface than that heretofore provided by any of the prior constructions and a more effective surface, particularly for certain purposes. Preferably means is provided for varying the width 65 of the surface on the bolster which co-operates at any given time with the tool. To facilitate ready adjustment of the bolster to present a fresh surface when the surface 70 opposed to the tool becomes too worn, the illustrated bolster is secured along its longitudinal edges to two rollers so that it may be rolled off of one roller on to the other step by 75 step to any desired extent. Conveniently, one of the rollers is utilized to serve as means for yieldingly applying tension of a selected 80 maximum amount to the bolster, whereby the bolster may accommodate itself to variations in the thickness of the work.

The invention contemplates also the provision of a yielding backing for the bolster constructed to yield along a multiplicity of lines so that the latter bolster may accommodate the more readily variations in the thickness of the work. Conveniently the yielding 85 backing for the bolster is furnished by a pneumatic member embraced by an unyielding casing to provide proper support for the member. In the illustrated construction, the casing is a rigid hollow cylinder slotted 90 along one side to expose the contained pneumatic member as a support for the bolster where the latter receives the thrust of the treating tool.

Other features of the invention and novel 100

combinations of parts will be described in the detailed specification and set forth in the appended claims.

In the drawings,

5 Fig. 1 is a plan view from above and partly in section showing one embodiment of the invention;

Fig. 2 is a transverse, vertical view of parts of the machine shown in Fig. 1;

10 Fig. 3 is a view similar to Fig. 2 but showing the parts in work-treating position; and

Fig. 4 is a detail view partly in section disclosing the construction of the pneumatic member and its mounting.

15 In the illustrated machine the work treating tool is a cylinder 10 having blades 12 helically arranged on the surface of the cylinder and extending in opposite directions from points intermediate between the ends 20 of the cylinder as most clearly disclosed in Fig. 1 of the drawings. As shown, the cylinder 10 is mounted for rotation in bearings in side members 11 of the machine frame. This cylinder 10 is provided with blades for performing unhairing operations. It will be understood, however, that any one of a number of cylinders with blades adapted to the performance of other operations on hides, skins and leather may be substituted for the 30 cylinder shown without departing from the principles of the invention. For supporting the work for the operation of the tool 10 there is provided a broad, flexible member or bolster 14 and a yielding, supporting or backing member for the bolster indicated by reference character 16 and hereinafter described in detail.

As illustrated, the flexible member or bolster 14 comprises a mat preferably made of vulcanized rubber and provided with a heavy canvas backing, the canvas backing member being extended beyond the mat or bolster proper to afford attaching portions 20, 21 adapted to be attached to supporting members which, in the construction shown, are rollers 22, 24.

In beginning operations with a new machine, or at least with a new bolster, the latter is wound upon the roller 22 (Fig. 2) to 50 such an extent as to leave one end surface of the bolster in contact with the tool 10, this end of the bolster being secured against displacement by means of the fabric or canvas extension 21 which is wound upon the other roller 24 (Fig. 2). After the bolster has 55 served for a considerable period in its first position it may be adjusted when worn by winding up on the roller 24 and simultaneously therewith unrolling a portion of the bolster from the other roller 22. This 60 adjustment of the bolster is repeated from time to time until all of the bolster surface has been utilized as a work support, it being preferable to have both ends of the bolster provided with fabric or canvas portions simi-

lar to that shown more clearly at 21 in Fig. 2, the other canvas portion being indicated at 20 on the roller 22 (Fig. 2). After the rollers have been rotated to position the bolster as desired the roller 22 is secured fixedly 70 in position by relatively heavy set screws one of which is shown at 25, the other roller 24 being secured against displacement through a pawl and ratchet mechanism 28, 30, of which the pawl 28 is held in operative position by a spring 32.

In order that the roller 24 may operate also as a tensioning means for the bolster it has preferably mounted upon it a pair of lever arms 34 pivoted on end portions 36 80 (Fig. 1) of the roller 24 which is rotatably mounted in a carrier 37 slidable on the side frames 11 of the machine. Each lever 34 is provided with a weighted member 44 adjustable along the lever extension 46 so as to 85 enable the operator to apply any desired tension upon the bolster. Since the ratchet 30 is secured to the roller 24 and the pawl 28 is positioned within a bifurcation of the lever 34, the lever may be used as a hand-operated 90 means for turning the roller 24 to wind up the bolster 14 thereon and also to apply the desired tension to the bolster. The amount of tension may be determined through adjustment of the weighted member 44 and 95 through adjustment of a supporting member 50 for the lever 34. Since there is a lever 34 together with the ratchet and pawl mechanism 28, 30 at each end of the roller 24 it is possible for one workman to adjust the tension upon the bolster, it being preferable, however, for both levers to be operated at 100 substantially the same time.

Conveniently, and as shown, the weighted levers 34 serve also as means for yieldingly 105 tensioning the bolster 14. Since, as already stated, the ratchet wheels 30 are secured to the ends of the roller 24, unusual pressure on the bolster 14 occasioned, for instance, by especially thick portions of the work or an 110 unusually heavy piece of work, will tend to turn the roller 24 and, on occasion will actually turn said roller in an unwinding direction with respect to the bolster 14, this reverse rotary movement of the roller being 115 permitted through a lifting movement of the two levers 34. It will be understood that the levers will immediately return to normal position following the passage of the thicker portion of the work and that the maximum 120 tension on the bolster, before any yielding takes place, may be regulated through adjustment of the weight 44 on the arm 46 of the lever 34 and further through adjustment of the member 50, as will hereinafter be described. As an additional means for controlling the tension of the bolster, the supporting member 50 is passed loosely through a projecting boss 52 on the carrier 37 and has this 125 end provided with a convexly-surfaced but- 130

ton 55 for seating in a cup in the boss 52, the end of the member 50 being screw-threaded to support adjusting and lock nuts 56 and 57. The lower end of member 50 is pivoted at 58 to the lever arm 34. It will be understood that adjustment of the member 50 will serve to vary the position of the lever 34 and thus provide for adjustment of the tension on the bolster.

10 Means is provided for causing the bolster 14 to present a relatively broad surface to the tool 10, this means in the construction shown comprising a roller 60 (Fig. 4) extending longitudinally of the bolster and parallel 15 with the tool 10. As shown, the roller 60 is mounted in a supporting member 64 carried by a bracket 62 securely attached to the carrier 37 so as to move bodily with the rollers 22, 24 and the backing member 16 during 20 movement of these parts in directions toward and away from the tool 10. Hence, when the carrier 37 is in retracted position (shown in Fig. 2 of the drawings) the bolster is not disturbed in its position nor in its tension. 25 As stated the roller 60 is mounted directly upon the supporting member 64 adjustable on the bracket 62, thus making it possible to vary the position of the roller 60 with respect to the tool 10 and the yielding backing member 16, whereby the bolster may be caused to 30 present a surface of desired width for contact with the curved surface of the tool 10. For instance, if the supporting member 64 should be adjusted toward the left in Fig. 3 of the drawings, the bolster 14 would be so positioned as to embrace a larger portion of the curved surface of the tool 10 than is disclosed in said figure. Ordinarily the bolster will occupy the position shown in Figs. 2 and 3 when it is especially effective in co-operation with the tool in unhairing and scudding operations. For purposes of adjustment the member 64 at each end of the roller 60 is provided with a screw threaded member 66 fixedly secured thereto and extending through a 45 projecting part 68 of the bracket 62. Upon proper manipulation of the nuts 70 on the screw threaded member 66 the supporting member 64 may be adjusted and secured in such adjusted position as may be found desirable. With the bar or roller 60 adjusted to the right, in Figs. 2 and 3, the bolster may be tensioned to be in a plane tangential to the cylindrical surface of the tool 10, in which 50 condition it would co-operate with the proper tool to greater advantage in such a hide or leather-treating operation as fleshing.

55 In the illustrated machine, the yielding backing member 16 comprises an inside pneumatic tube 80 (Fig. 4) enclosed in a heavy canvas casing or shoe 82, the pneumatic tube and the casing being of a size to fit snugly within a rigid hollow cylinder 84 supported fixedly at its ends in side portions of the carrier 37, means being provided at one end of

the cylinder and pneumatic tube 80 to introduce air into the latter under pressure from any desired source, such as an air pump (not shown), one of the bearings 86 for the cylinder being hollow, for the passage of the air 70 tube 88. In order that the yielding backing member 16 may have a portion of its surface exposed for contact with the bolster 14 the cylinder 84 has a relatively wide slot 90 extending lengthwise of the cylinder opposite 75 to the adjacent surface of the tool 10, the center line of the slot 90 being in a plane passing through the axes of the cylinder 84 and the tool 10. In the preferred construction illustrated, the relatively heavy canvas casing 80 82 comprises a cylindrical portion having end portions 94 which are receivable each in a groove provided by a reduced portion 96 of the screw threaded end members 98 and 99 of the metal cylinder 84. Within the cylindrical portion of the canvas casing 82 adjacent each end thereof is a pair of disks 100 of the same material and serving to act as end protecting means for the rubber pneumatic tube 80, one of the disks 100 being perforated to accommodate a pipe 102 extending from the pneumatic tube. The illustrated pipe 102 is without a valve since it has been found more desirable to control the inflation of the pneumatic tube 80 by means of valves 95 in the pneumatic pump provided for the purpose of inflating the tube 80.

100 Considerable friction and heat tends to develop between the bolster 14 and the shoe 82 of the yielding backing member 16 due to vibration of the bolster caused by the blades striking against the bolster at a high rate of speed. To overcome any possible disadvantage from this condition, means is provided to cool the contacting surfaces, the said means comprising in the construction shown a spraying device in the form of a perforated pipe 103 through which cold water may be allowed to flow at any desired pressure from a source not shown.

105 For feeding the work over the bolster 14 and past the tool 10 there is provided, in the construction shown, a number of feed rolls.

110 Of these rolls the one at 110 (Fig. 3) is rubber covered so as to engage frictionally 115 with the work and is mounted at each end upon an arm extending up from the carrier 37. Carried in a bracket 112 is a second feed roll 114. Between these two rolls there is a third roll 116 which serves as a pinch roll 120 movable along a slot 118, in a bracket extension 120, into and out of co-operative relation with respect to the feed rolls 110, 114. The roll 116 is moved upwardly into inoperative position at the same time that the carrier 37 is retracted and in this position the work W may be readily introduced. Upon movement of the carrier 37 toward the tool 10 the pinch roll 116 descends to press the work 125 against the feed rolls 110, 114 whereby the 130

work is dragged past the operating tool 10 and over the bolster 14.

When one part of the work has been operated upon, substantially one-half thereof, the operator trips the usual treadle to cause a second retraction of the carrier 37 so that the work may be removed, reversed, and reintroduced into the machine to complete the operation upon the remaining portion. For a more complete disclosure of the operating means for the feed rolls and for the carrier 37, reference should be had to United States Letters Patent No. 696,588, granted April 1, 1902, upon application of F. J. Perkins, and to No. 845,640 granted Feb. 26, 1907, upon application of H. A. Holder. While a roll similar to the feed roll 110 herein illustrated serves in the Perkins machine as a bed roll as well as a feed roll, the mounting and movement of the two are the same in the two machines. It is further pointed out that the construction and arrangement of the feed rolls of the illustrated machine are fully shown in said United States Letters Patent No. 845,640. It should be stated that the bracket 112 which carries the feed roll 114 and the pinch roll 116 is slideable on the carrier 37 and is held under spring pressure, as disclosed in the patents cited, which constantly urges the bracket 112 to press the two rolls 114, 116 yieldingly in the direction of the roll 110. Hence, when the pinch roll 116 is pulled downwardly along the slot 118 it engages with the work W and forces it into contact with both of the rolls 110, 114. Furthermore, the carrier 37 is constantly under a yielding pressure provided by springs, not shown, operative to permit a yielding of the backing roll 16 in case an unusually thick piece of work is introduced between the cylinder 10 and the bolster 14, the same yielding of the backing member 16 taking place when an unusually thick portion of a piece of work is being operated upon. This particular mounting of the bracket 112 and of the carrier 37 by which they yield in the manner described when thick portions of the work are passing is not shown in detail since it forms part of an old and well known construction shown, for instance, in the Perkins and Holder patents, already cited.

Having described my invention, what I claim as new and desire to secure by Letters Patent is:—

1. In a machine of the character described, a tool for treating hides, skins or leather, and means for supporting the work for the operation of the tool comprising a flexible member, and a pneumatic member for yieldingly supporting the flexible member along the line of application of the tool to the work.

2. In a machine of the character described, a tool for treating hides, skins or leather, and means for supporting the work for the operation of the tool comprising a flexible member

adapted to present a relatively broad surface to the tool, and a member having a locally yielding surface for yieldingly backing the flexible member along the line of application of the tool.

3. In a machine for operating upon hides, skins or leather, a cylinder having a blade for operating on a piece of work, means for supporting the work for the operation of the cylinder comprising a flexible member extending the full length of the blade and partially around the surface of the cylinder, and means having a locally yielding portion for yieldingly backing the flexible member along the line of application of the blade to the piece of work.

4. In a machine for operating on hides, skins or leather, a tool for operating on a piece of work, work supporting means comprising a pneumatic backing member, a bolster interposed between the tool and the pneumatic member, and means for mounting the bolster having a supporting surface for the bolster located in front of the pneumatic member, said mounting means being adjustable to tension the bolster so that in conjunction with the mounting thereof the bolster is caused to present a broader surface to the tool than would be afforded by the pneumatic member.

5. In a machine for operating upon hides, skins or leather, a tool for operating on a piece of work, a bolster adapted to support the work for the operation of the tool, a pneumatic member extending across the bolster to form a yielding backing for the latter, and an unyielding support for the pneumatic member arranged partly to surround the pneumatic member and to expose part of the pneumatic member for contact with the bolster.

6. In a machine, for operating on hides, skins or leather, a bladed cylinder for operating on a piece of work, a bolster adapted to support the work in contact with a substantial portion of the bladed cylinder, a pneumatic member back of the bolster for forming a yielding backing for the latter, and an unyielding casing for the pneumatic member having a portion cut away to expose part of the pneumatic member for contact with the bolster.

7. In a machine for operating on hides, skins or leather, a cylinder having blades for operating on a piece of work, a bolster for supporting the work against the cylinder, means for applying tension to the bolster, and other means for yieldingly backing the bolster along the lines of application of the blades of the cylinder to the work comprising a pneumatic member and a member for rigidly supporting the pneumatic member.

8. In a machine for operating on hides, skins or leather, a cylinder having blades for operating on a piece of work, a bolster for supporting the work against the cylinder,

means for applying yielding tension to the bolster, and a pneumatic member for yieldingly backing the bolster against the thrust of the blades of the cylinder.

5 9. In a machine for operating on hides, skins or leather, a tool having a blade for operating on a piece of work, work supporting means comprising a pneumatic roll and a bolster interposed between the tool and the 10 pneumatic member, and means for supporting the bolster so as to cause it to present a broader surface to the tool than would be afforded by the pneumatic member.

10 10. In a machine for operating on hides, skins or leather, a tool for operating on a piece of work, a bolster for supporting the work against the operation of the tool, means for backing the bolster along the line of application of the tool to the work, a member over 20 which the bolster is passed, and means for adjustably supporting the member to vary the breadth of the surface of the bolster in cooperation with the backing means and the tool to suit various classes of work.

25 11. In a machine for operating on hides, skins or leather, a cylinder having blades for operating on a piece of work, a bolster for supporting the work against the operation of the cylinder, means for yieldingly tensioning 30 the bolster so that it may accommodate itself to variations in the thickness of the work, a pneumatic member for backing the bolster along the lines of application of the blades to the piece of work, and a member affording un- 35 yielding support to the pneumatic member.

12. In a machine for operating on hides, skins or leather, a bladed cylinder rotatable for operating on a piece of work, means for supporting the work for the operation of the 40 cylinder comprising a flexible member extending the full length of the cylinder and partially around the surface thereof, means for yieldingly tensioning the flexible member so that it may accommodate itself to variations 45 in the thickness of the work, and a stationary member having a locally yielding surface for yieldingly backing the flexible member along the line of application of the bladed cylinder.

13. In a machine for operating on hides, 50 skins or leather, a bladed cylinder for operating on a piece of work, a bolster for supporting the work against the thrust of the cylinder, a member to which one end of the bolster is attached, a roller to which the other end of the bolster is attached, said roller being rotatable to apply tension to the bolster, and a stationary member having a locally yielding portion for yieldingly backing the bolster along the line of application of the bladed cylinder.

14. In a machine for operating on hides, 55 skins or leather, a tool for operating on a piece of work, a bolster for supporting the work for the operation of the tool, a pair of rollers to each of which one end of the bolster is attached so that the bolster may be rolled

off of one roller and onto the other roller in adjusting the work surface of the bolster with respect to the tool, and means for operating one of the rollers to apply tension of a selected maximum amount to the bolster.

70 15. In a machine for operating on hides, skins or leather, a tool for operating on a piece of work, a bolster for supporting the work against the thrust of the tool, a member to which one end of the bolster is attached, a 75 roller to which another end of the bolster is attached, said roller being rotatable to apply tension to the bolster, and a weighted member operative to rotate the roller and to maintain the tension on the bolster yieldingly at a selected maximum amount.

16. In a machine for operating on hides, skins or leather, a tool for operating on a piece of work, a bolster for supporting the work against the thrust of the tool, a roller 85 to which one end portion of the bolster is attached, a second roller to which the opposite edge portion of the bolster is attached, both rollers being rotatable so as to shift the bolster to bring a new work supporting surface 90 thereon in position opposed to the tool, and a pair of members operative to apply a maximum tension to the bolster.

17. In a machine for operating on hides, skins or leather, a tool for operating on a piece of work, a bolster for supporting the work against the tool, means for applying tension to the bolster, a pair of rollers to each of which one end of the bolster is attached so that the bolster may be rolled off of one roller 95 onto the other roller, and a lever for operating one of the rollers to apply tension on the bolster and to maintain the tension at a selected maximum amount.

18. In a machine for operating on hides, skins or leather, a tool for operating on a piece of work, a bolster for supporting the work against the thrust of the tool, a roller to which one end portion of the bolster is attached, a second roller to which the opposite end portion of the bolster is attached, both 100 rollers being rotatable so as to shift the bolster to bring a new work supporting surface thereon in position opposed to the tool, and a third roller over which the bolster is passed to permit adjustment of the bolster in directions toward and from the tool.

115 19. In a machine for operating on hides, skins or leather, a tool for operating on a piece of work, a bolster for supporting the work for the operation of the tool, a support for fixedly holding one end of the bolster during operation of the machine, and means for adjusting the bolster to present a new surface when a given surface has become worn.

120 20. In a machine for operating on hides, skins or leather, a tool for operating on a piece of work, a bolster for supporting the work for the operation of the tool, and a pair of rollers to each of which one end of the bolster is at- 130

tached and arranged so that the bolster may be rolled off of one roller and onto the other roller in adjusting the work surface of the bolster with respect to the tool.

5 21. In a machine for operating on hides, skins or leather, a tool for operating on a piece of work, a bolster for supporting the work against the tool, end supports for the bolster, a yielding member for backing the bolster

along the line of application of the tool to 10 the work, and a member spaced apart with respect to the yielding member to co-operate with the latter in supporting the bolster so that the latter presents a broad surface to the tool.

15 In testimony whereof I have signed my name to this specification.

CHARLES H. BECKER.
